ATTORNEY'S.

UNITED STATES PATENT OFFICE.

WILLIAM P. FEST, OF BROOKLYN, NEW YORK, ASSIGNOR TO THE J. B. BREWSTER & COMPANY, OF NEW YORK.

DESIGN FOR A CARRIAGE-BODY.

SPECIFICATION forming part of Design No. 20,065, dated July 29, 1890.

Application filed April 5, 1890. Serial No. 346,795. Term of patent 7 years.

To all whom it may concern:

Be it known that I, WILLIAM P. FEST, a citizen of the United States, residing at Brooklyn, in the county of Kings and State of New York, have invented and produced a new and original Design for a Carriage-Body, of which the following is a specification, reference being had to the accompanying drawings, forming part thereof, in which—

Figure 1 is a side view. Fig. 2 is a front view.

The leading feature of my design consists in the forward extension of the exterior surface of what is known among carriage-designers as the "coupé-pillar," thereby making the general sweep of the carriage-sides in sub-

stantially continuous lines from the rear to the front of the extension-front, as shown. The sides of the carriage-body, commencing at *a*, round outward to about *b* and thence round inward to about *c*. The extreme forward portion of this surface may be provided with a border *d*, forward of which a sunken panel *e* may be employed.

What I claim is—

The design for carriage-bodies herein shown and described.

WILLIAM P. FEST.
